US00D515585S

(12) **United States Design Patent** (10) Patent No.: **US D515,585 S**
(45) Date of Patent: **** Feb. 21, 2006**

(54) **COMPUTER MEMORY DEVICE**

(75) Inventor: **Steven A. Landau**, Voorhees, NJ (US)

(73) Assignee: **KASL Enterprises, Inc.**, Bala Cynwyd, PA (US)

(**) Term: **14 Years**

(21) Appl. No.: **29/215,373**

(22) Filed: **Oct. 18, 2004**

(51) LOC (8) Cl. **14-02**

(52) U.S. Cl. **D14/432**

(58) Field of Classification Search **D14/432, D14/435, 436, 438; D21/333, 324, 328, 713, D21/707, 709; 463/43-5; 361/737; 473/593, 473/604, 52**

See application file for complete search history.

(57) **CLAIM**

The ornamental design for a computer memory device, as shown and described.

DESCRIPTION

FIG. 1 is a side perspective view of a computer memory device of the present invention;

FIG. 2 is a front view of the computer memory device of FIG. 1, the rear view is a mirror image;

FIG. 3 is a side view of the computer memory device of FIG. 1, the opposite side is a mirror image;

FIG. 4 is a top view of the computer memory device of FIG. 1; and,

FIG. 5 is a bottom view of the computer memory device of FIG. 1.

The broken line drawing in FIGS. 1-4 is for illustrative purposes only and forms no part of the claimed design.
